UNITED STATES PATENT OFFICE.

CHARLES H. BARTLETT, OF CAMBRIDGE, MASSACHUSETTS.

HOLDER FOR TELEPHONES AND OTHER ARTICLES.

1,161,762.

Specification of Letters Patent. Patented Nov. 23, 1915.

Application filed October 5, 1912. Serial No. 734,212.

To all whom it may concern:

Be it known that I, CHARLES H. BARTLETT, a citizen of the United States, and resident of Cambridge, in the county of Middlesex and State of Massachusetts, have invented 5 certain new and useful Improvements in Holders for Telephones and other Articles, of which the following is a specification.

This invention relates to supports for articles such as telephones, electric or other lamps, and other devices which are to be removed from and replaced upon their supports.

The object of the invention is to provide 15 a support from which the telephone or other article can not possibly be accidentally displaced, but from which it can be removed when desired as readily as though resting on a plain flat surface such as a desk 20 top, shelf, or chair arm or bracket.

To this end, the invention consists in a support having catches which automatically engage the telephone instrument or other article so that it can not be moved off laterally or by tilting, but which will automatically release the said article when the latter is lifted.

The invention further consists in the improvements substantially as hereinafter described and claimed.

Of the accompanying drawings: Figure 1 is an elevation of my improved support in one of its embodiments, the outer end of the bracket or attaching arm being broken away; Fig. 2 represents a vertical section of the same; Fig. 3 is a plan view. Figs. 4 and 5 are views similar to Fig. 1, but illustrating modifications, the catches being open.

Similar reference characters indicate the same or similar parts in all the figures.

Lower and upper members 10 and 11 respectively are illustrated as disks, but it is to be understood that they may be so cut out as to present a plurality of radial arms, for the catches presently described. For brevity of description, without limitation, said members will be referred to as disks. The lower disk is firmly supported in the desired fixed position, and has a plurality of upright guides 12, the upper ends of which extend outwardly, preferably in curved form as shown at 13. The upper disk 11 is yieldingly movable toward the lower one and constitutes the immediate support on which the telephone instrument indicated

by dotted lines in Fig. 1 normally rests when not in use. Said dotted lines may however represent a lamp or any other article. Said upper disk has catches 14 pivoted thereto, as 60 at 15, said catches having loops 16 which engage the guides 12 so that as the upper disk moves downwardly under the influence of the weight of the article placed upon it, the catches will swing inwardly to the position 65 shown in Fig. 1, rendering it impossible for the article to be knocked off from its support. But when the article is lifted up, the guides cause the catches to swing outwardly to the position shown in Fig. 2 and entirely 70 release the article. Preferably the upper disk will be retained in the latter position by a spring, such as presently described, until the article is returned to the support. The ends of the catches are shown as provided 75 with tips 17 of soft material to prevent marring the article. When the latter is an electric appliance, it is well to make such tips of suitable insulating material. The lower disk is shown as secured to a central 80 socket 18, which, in turn, is secured to one end of an arm or bracket 19 as by a set screw 20. It is to be understood that the arm or bracket 19 is secured to any firm support such as a desk, a special stand, or chair arm. 85 A plunger or vertical guide 21 projects from the upper disk down into the socket 18 and bears on a spring 22 in the latter. Preferably the end of the bracket arm 19 is formed as a sleeve 23 in which the socket 18 is removably secured by the set screw 20.

The plunger 21 not only serves as the connection between the spring 22 and the depressible rest 11 so that the latter will rise and release the catches when the article is 95 lifted, but it also acts to guide the said rest 11 and prevent the latter from tilting. This prevents the article from being tilted off because neither one of the catches can act in advance of the others so as to let one side of 100 the base of the article rise. In other words, all the catches must operate simultaneously or in unison, this being due to the disk 11, which operates all the catches, and the fact that said disk cannot rock or tilt so as to 105 permit one catch to open and let the article tilt. The plunger 21 guides the rest 11 so that the latter is always parallel with the plane of the lower member 10, and consequently all of the catches must open or close 110 simultaneously and they can not open so long as any part of the supported article re-

mains low enough to hold the rest or disk 11 down.

Fig. 4 shows a modified construction in which the members 10 and 11 are externally connected, as by a U-shaped spring arm 30 which normally supports the member 11 yieldingly and permits it to be depressed toward the member 10. Such spring arm enables the socket 18, spring 22, and plunger 21 of Fig. 2 to be dispensed with. Although such structure does not insure absolute parallelism of the members 10 and 11 at all times, the deviation is so slight as to be negligible for many purposes. Instead of the arm 30 being continuous, it may be made of two pieces as indicated at 31, 32, in Fig. 5, such two pieces being hingedly connected at 33 and yieldingly held apart by a spring 34.

Having described my invention, I claim:

1. A device of the character described comprising a support having movable catches, means operated by the placing of an article on said support or lifting it therefrom for simultaneously operating said catches inwardly or outwardly, and means for guiding all of the catches to cause them to act in unison whereby neither catch can yield to permit tilting of the article on the support.

2. A device of the character described comprising a support, spring-controlled means for yieldingly holding the support in a raised position and permitting its depression by an article deposited on it, and catches engaged with said article by the depression of the support to prevent the article from being tilted on or removed laterally from the support, and automatically moved and held out of engagement with said article by the support when the article is lifted.

3. A device of the character described comprising a vertically movable article support, movable catches connected therewith, a lower member toward which said support is movable under the influence of the weight of an article on the support, connections between the said lower member and the catches to insure simultaneous inward action of the

catches, and means for preventing either catch from moving outwardly until all the catches are free from the said article.

4. A device of the character described comprising upper and lower disks, the upper one being yieldingly movable toward the lower one under the influence of the weight of an article on the upper one, a plurality of guides carried by the lower disk, a similar plurality of catches pivoted to the upper disk, and sliding connections between said catches and guides. 55

5. A device of the character described comprising upper and lower disks, the upper one being yieldingly movable toward the lower one under the influence of the weight of an article on the upper one, a plurality of guides carried by the lower disk, a similar plurality of catches pivoted to the upper disk, and sliding connections 60 between said catches and guides, means being provided for preserving the upper and lower disks in parallelism. 70

6. A device of the character described comprising a socket, a spring therein, upper and lower disks, the upper disk having a plunger bearing on said spring, guides having outwardly turned upper ends carried by the lower disk, and catches pivoted to the upper disk and having sliding connections with said guides. 75

7. A device of the character described comprising a support having movable catches adapted to grasp an article placed on the support, and connections whereby said catches will be operated inwardly when an article is placed on the support and outwardly when such article is lifted from the support, said connections including means for preventing outward movement of either catch alone, whereby an article on the support is positively held against tilting movement. 85

In testimony whereof I have affixed my signature, in presence of two witnesses.

CHARLES H. BARTLETT.
